REFRIGERATION APPARATUS

Gregg F. Forsthoefel, Springfield, Mass., assignor
to Westinghouse Electric & Manufacturing
Company, a corporation of Pennsylvania

Application December 31, 1931, Serial No. 584,227

13 Claims. (Cl. 20—35)

My invention relates to refrigerator cabinet construction and particularly to means for effecting thermal insulation of refrigerator cabinets and the like.

5 Refrigerator cabinets have been constructed having inner and outer metallic walls with strips of non-hygrosopic non-metallic material such as sold under the trade names of bakelite or micarta connecting the walls of the cabinet, including both the cooling chamber and the closure therefor, peripherally of the opening of the cabinet. These strips are utilized for preventing moisture from entering between the walls and lowering the efficiency of the heat insulation of the cabinet, for offering resistance to the flow of 10 heat between the walls, for maintaining the walls in spaced relation and also for imparting a neat and finished appearance to the cabinet.

15 The inner and outer walls of the cabinet are 20 preferably not connected together by any material which is a good conductor of heat since the temperature differential between the inner and outer metallic walls of a refrigerator cabinet is great and heat is readily conducted into the food chamber of the refrigerator. Condensation on 25 the cabinet occurs for the most part between the inner and outer walls of the cabinet adjacent to the door closure, and is likely to warp any hygroscopic material in the vicinity thereof so that 30 moisture enters the insulation of the cabinet. For these reasons non-hygrosopic, non-metallic, and heat-insulating strips connecting the inner and outer walls of the cabinet are desirable, and as stated have been widely used.

35 Where a wooden framework has been disposed between the walls of the cabinet to provide for fastening of the strips to the cabinet, moisture may enter the wooden framework and increase its heat conductivity. Also, moisture may enter 40 the cabinet insulation because of the warping of the framework whereby the efficiency of the cabinet insulation is decreased.

45 It has also been suggested that the non-hygrosopic non-metallic strips be fastened directly to the walls of the cabinet; however, the strip may be subject to more or less strain at the regions of the fastening means, such as, for example, screws, due to differential expansion either of the wall elements of the box structure or of the door. 50 Furthermore, the strips and connections are subject to stressed conditions incident to opening and closing the door or handling the cabinet. These conditions may result in looseness about the screws, permitting moisture to enter the 55 insulation.

It is an object of my invention, therefore, to provide tight, non-hygrosopic, non-metallic, and heat-insulating strips between the inner and outer walls of a refrigerator cabinet or the like, which are fastened to the walls by suitable clamping means, which obviate the necessity of providing a wooden framework between the walls of the cabinet peripherally of the opening thereof.

5 It is another object of the invention to provide clamping means for the above-mentioned strips which are heat-insulating and heat-insulated and which will be flexible enough to compensate for differences in expansion of various elements of a refrigerator cabinet and for stresses and strains imposed upon the cabinet in use.

10 It is still another object of the invention to provide a thermal seal between the inner and outer walls of a refrigerator cabinet which is quickly and easily applied thereto.

15 It is a further object of my invention to provide a thermal seal between the inner and outer walls of a refrigerator cabinet which comprises non-hygrosopic, non-metallic heat-insulating strips fastened between the walls by clamping means, the strips and clamping means forming 20 the sole connection between the inner and outer walls of the cabinet peripherally of the opening thereof.

25 A further object of my invention is to provide, in connection with a non-hygrosopic, non-metallic, and heat-insulating cover or molding strip for a refrigerator door construction, clamping means carried by the strip which cooperates with the strip to keep the latter pressed against seating surfaces on the inner and outer walls of the 30 cabinet and which cooperates with the strip and the walls to resist relative displacement thereof.

35 These and other objects are effected by my invention, as will be apparent from the following description and claims taken in connection with 40 the accompanying drawing forming a part of this application, in which:

45 Fig. 1 is an elevational perspective view of a refrigerator cabinet constructed in accordance with an embodiment of my invention;

45 Fig. 2 is an enlarged partial sectional view of a refrigerator cabinet taken on line II—II of Fig. 1;

50 Fig. 3 is an enlarged perspective view of the clamping means utilized in my invention; and,

55 Fig. 4 is a cross sectional view of the clamping means taken on line IV—IV of Fig. 3.

55 My invention is concerned particularly with an improved door construction connection between the inner and outer walls either of the box

at the door region or of the door, the connection including non-hygrosopic and heat insulating molding strips preferably overlapping marginal portions of the walls, together with clamping means for holding the strips in place and, for resisting relative displacement of the strips and the inner and outer walls. The expression "door construction" is used hereinafter to indicate the connecting means and the walls connected there-
10 by as applied either to the box or to the door.

In accomplishing the objects of the invention, I provide, in connection with the non-hygrosopic non-metallic, heat insulating strips, clamping means of thin resilient metal which prefer-
15 ably extend the entire length of each side of the cabinet peripherally of the opening thereof, and which engage the inner and outer walls so that edge portions of the latter are clamped between the non-hygrosopic, non-metallic strips
20 overlapping the edge portions and the resilient metal. Heat insulating material is preferably disposed between the metal clamping means and the metal walls. The inner and outer door construction peripheral wall edges are bent or flanged
25 backwardly with respect to the non-hygrosopic, non-metallic strip seating surfaces and the clamping means is recessed so that the flanges and recesses cooperate somewhat like tongue and groove connections to resist relative displacement
30 of the non-hygrosopic, non-metallic and inner and outer walls. The non-hygrosopic, non-me-
35 tallic strips are held in place by the clamping means and the strips and clamping means are held together by screws passing through openings in the strip and the clamping means and engag-
40 ing resilient speed nuts fastened to the clamping means. The strips are, therefore, held tightly and resiliently in place by the clamping means, and the two form a connecting member which
45 provides the sole connection between the walls of the cabinet, the insulating material on the metal walls being considered as a part of the wall, if used. The clamping means, by extending peripherally of the door construction, assists in forming a moisture proof seal for the space between the walls of the cabinet containing heat insulating material.

Referring specifically to the drawing for a detailed description of the invention, numeral 1 designates generally a refrigerator cabinet including a box structure 2 having an opening 3 and a door 4. The box structure 2 has inner and outer metallic walls 5 and 7, and the door 4 is likewise constructed with inner and outer metallic walls 9 and 11. Heat insulation 8 is disposed between the walls of the cooling box structure 2 and the door 4, and a gasket 10 is provided between the cooling box 2 and the door 4.

The inner and outer box walls 5 and 7 are bent
60 to provide marginal portions 11a and 12 having outer seats 13 and 14 for the non-hygrosopic and heat-insulating strip 15 overlapping and seated against the seats. The strip 15 is held seated by means fully described hereinafter.

65 The door walls 9 and 11 are especially modified to provide outer seats for the strip 15 in a manner similar to that already described. The inner wall 9 has a marginal portion 19 providing an outer seat 20. The outer wall 11 is folded over
70 to provide the usual door overlapping portion 21, to the back face of which is secured the gasket 10, the gasket having a flange portion 22 having a front seat 23. It will, therefore, be apparent that the seat 23 is provided on a part which is in effect
75 integral with the outer wall 11. The non-hygro-

scopic and heat insulating strips 15 for the door are seated against the outer seats 20 and 23.

Referring now to the means for holding or clamping the non-hygrosopic and heat-insulating strips 15 in contact with the seats 13 and 14 and the seats 20 and 23 with the strips overlapping the seats, the marginal portions 11a and 12 are provided with backwardly-extending flange portions 24 and 25 and the marginal portion 19 of the inner wall 9, and the outer wall 11 are pro-
10 vided, respectively, with backwardly-extending flange portions 26 and 27. An inner resilient metallic strip 28 is secured to each outer strip 15 by suitable means, for example, by the screws 29, and the inner metallic strips are preferably re-
15cessed to provide longitudinally extending side grooves 30 arranged to cooperate with the back-
wardly-extending flanges 24, 25, 26 and 27 to hold the heat-insulating and non-hygrosopic strips 15 and the inner and outer walls in place. 20

The resilient metallic strip elements 28 are so constructed and related to the inner and outer walls as to minimize heat transmission. Instead of using an inner spring strip of sheet form, the latter is cut out to provide a lattice-like forma-
25 tion consisting of side members 31 connected by cross bars 32, and the structure is deformed so as to increase its stiffness, permitting of light material of minimum cross section with consequent low heat transmission and with retention 30 of maximum stiff spring action. The modification for this purpose, as shown, preferably consists in making the side members 31 in channel form or arcuate in cross-section to provide the recesses 30 already referred to, and the cross bars 35 32 also include trough-like or rib formations to give stiffness. Preferably, the inner metallic strips 28 are made of an alloy steel having low heat conductivity, for example, stainless steel. In addition to the structural design providing mini-
40 mum heat transmission area and the use of material having high heat resistance, resistance to the transmission of heat is preferably further increased preferably by the provision of insulating material 33 between the side members 31 and the flanges 24, 25, 26 and 27. 45

The inner spring strip 28 is preferably connected to the outer non-hygrosopic and heat-
insulating strip 15 by screws passing through suitable apertures formed in the strips 15 and in the cross bars 32. Speed nuts 34 are carried by the cross bars at the rear sides thereof, the speed nuts preferably consisting of bowed strips each spot-
welded at one end to the cross bar, as shown at 35.

From the foregoing, it will be apparent that I 55 have provided a heat-insulating and non-hygrosopic strip which overlaps marginal portions of inner and outer walls in a refrigerator door construction, the strip cooperating with means which not only maintains the strip seated but also holds the strip and inner and outer walls in place. Since the non-hygrosopic heat-insulating strip is not fastened directly to inner and outer walls but merely rests thereon, and since the connection between the inner spring strip and the inner and outer walls is of the tongue-and-groove type, it will be apparent that the inner and outer walls may be subject to differential expansion and contraction effects or to shocks without stressing the structure at the connecting regions. Furthermore, connection of the inner and outer walls and maintenance of the heat-insulating and non-hygrosopic strip in position are effected in a way to minimize the transmission of heat, the spring strip preferably being constructed to resist 70 75

heat flow, being made of material having low heat conductivity and also preferably being spaced from the walls by means of heat-insulating material.

5 While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

15 1. In a refrigerator cabinet construction, inner and outer metallic walls separated by heat-insulating material and provided with margins having outer and inner seat portions, a non-hygrosopic and heat-insulating strip overlapping and seated against the outer seat portions, and spring means carried by the strip and cooperating with said inner seat portions to maintain the strip seated.

20 2. In a refrigerator cabinet construction, inner and outer metallic walls separated by heat-insulating material and provided with margins having outer and inner seat portions, a non-hygrosopic and heat-insulating strip overlapping and seated against the outer seat portions, spring means carried by the strip and cooperating with the inner seat portions to hold the strip seated, and heat-insulating material interposed between the spring means and the inner seat portions.

25 3. In a refrigerator cabinet construction, inner and outer metallic walls separated by heat-insulating material and having outer seat portions and inwardly-extending flange portions, a non-hygrosopic and heat-insulating strip overlapping and seated against the outer seat portion, and spring means having grooves cooperating 40 with said flanges to maintain the strip in place.

40 4. In a refrigerator cabinet construction, inner and outer walls provided with margins having outer seats and inwardly-projecting flanges, a non-hygrosopic and heat insulating strip overlapping and seated against said seats, clamping means connected to the strip and having recesses cooperating with the flanges to hold the strip and the walls in place.

45 5. The combination as claimed in claim 4 with 50 heat-insulating material interposed between the recesses and the flanges.

55 6. In a refrigerator cabinet construction, inner and outer walls separated by heat-insulating material and provided with margins having outer seats and inwardly-projecting flanges, an outer non-hygrosopic and heat-insulating strip overlapping and seated against said outer seats, an

inner spring strip secured to the outer strip and having side grooves cooperating with the flanges to hold the outer strip and the inner and outer walls in place.

5 7. The combination as claimed in claim 6 with a heat-insulating material interposed between the grooves and the flanges.

8. In a refrigerator cabinet construction, inner and outer walls separated by heat-insulating material and provided with margins having outer seats and inwardly-projecting flanges, an outer non-hygrosopic and heat-insulating strip overlapping said seats and seated against the latter, an inner spring strip having longitudinally-extending side grooves cooperating with said flanges 15 to maintain the outer strip seated against the outer seats and to hold in place the outer strip and the inner and outer walls, and screw means for connecting the inner and outer strips.

20 9. In a refrigerator cabinet construction, inner and outer walls separated by heat-insulating material and provided with margins having outer seats and inwardly-projecting flanges, an outer non-hygrosopic and heat-insulating strip overlapping and seated against said outer seats, an 25 inner resilient strip of lattice-work formation having channel side members connected by cross bars, the channel side members cooperating with said flanges to maintain the outer strip seated and to hold in place the outer strip and the inner 30 and outer walls, and detachable means for connecting the inner and outer strips.

35 10. The combination as claimed in claim 9 wherein the inner strip is made of metal having high resistance to heat transmission.

35 11. The combination as claimed in claim 9 wherein heat-insulating material is interposed between the channels and the flanges.

40 12. A thermal seal between disconnected inner and outer metallic walls at the periphery of a door construction comprising a strip of non-hygrosopic material and spring clamping means of thin metal secured to the strip, said spring clamping means and the strip being constructed and arranged to hold edge portions of the walls 45 and to maintain the strip seated in overlapping relation with respect to the walls.

45 13. A thermal seal between disconnected inner and outer metallic walls at the periphery of a door construction comprising spring clamps of 50 thin alloy steel of relatively low heat conducting qualities and strips of non-hygrosopic material, the spring clamps being fastened to the strips and engaging the inner surfaces of the inner and outer disconnected walls, the strips 55 engaging the outer surfaces thereof.

GREGG F. FORSTHOEFEL.
